AMPLIFIER STATION FOR DEEP-SEA SIGNALING CABLES

Application filed December 10, 1930, Serial No. 501,424, and in Germany December 18, 1929.

Whilst the development of the art of amplification in telegraphy and telephony used in land cables has led to the bridging over of very great distances, in the case of long 5 submarine cable distances the amplifier could be utilized for long submarine distances only to the extent that natural islands were available for the placing of the amplifiers in addition to the landing places of the cables. 10 The formation of artificial islands at places for the erection of amplifier stations for deep sea signaling cables encounters, owing to the wave movements of the surface of the sea, difficulties which can hardly be overcome by 15 the technical means which are available within the limits of expenditure which are imposed. However, since the wave movements of the sea decrease rapidly according to the depth, also in the case of the strongest amplitude there is a possibility of accommodating 20 the amplifier stations on supporting bodies which float under the sea at such depths where they are no longer affected by the wave movements on the surface of the sea. Generally 25 a depth of about 100 metres below the level of the sea shows no appreciable effect with respect to the surface waves. As in the case of greater depths only the general flow of the sea is perceptible, the speed of which 30 does not exceed a few millimetres or centimetres per second. Therefore a body which is not too large is subjected to comparatively small and uniform transverse strains.

The laying of an amplifier station in great 35 water depths or on the bottom of the sea is out of the question in the case of ocean cables owing to the large water pressures which come into question. Moreover the amplifier station must be accessible in a comparatively simple 40 manner from the surface of the sea.

An amplifier station according to the invention comprises two parts, viz. a floating supporting body which is stable as regards its floating, which is anchored at a depth of 45 about 100 metres under the level of the sea by means of steel hawsers and to which the signaling cable is led directly or through the intermediary of a separate connecting cable from the bottom of the sea and the actual 50 amplifier which is built in a water-tight cas-

ing resistant to pressure. Moreover, the station is so arranged that the amplifier can easily be brought up to the surface of the sea and let down again on to the supporting body in a reliable manner without it being necessary to interrupt the signaling operation on the cable. The bringing up of the amplifier from time to time is necessary from an operative point of view, as will be explained below.

One form of carrying the invention into effect is illustrated, by way of example, in Figures 1, 2 and 3 of the accompanying drawing.

Fig. 1 shows the floating supporting body in cross-section,

Fig. 2 illustrates a form of construction of the amplifier casing, and

Fig. 3 shows the whole of the amplifier station more or less diagrammatically.

Referring to Fig. 1, K is the floating supporting body which is stable in its floating. It has the form of an inverted, truncated cone, the upper surface of which forms a hollowed-out cone. The supporting body consists of a sheet metal casing made of a material which is resistant to sea-water and the interior of which is wholly filled with cork or a material of like small specific gravity, being reinforced by means of suitable stays. F are two holes which lead from the upper to the lower surface of the supporting body and which are intended to receive and guide the connecting cables between the signaling cable and the amplifier.

Referring to Fig. 2, V is the casing of the amplifier. Its upper part is cylindrical and the lower part conical, so that it can fit exactly into the conical depression formed in the supporting body. D is a dome provided on the said casing, through which the amplifier casing is made accessible. E and A are the incoming and outgoing cables of the amplifier. A supporting frame G is connected with the amplifier casing. To the points P₁ and P₂ there are connected the ends of a wire rope S which, by means of a small float B, forms a loop which remains vertical in the water.

Referring to Fig. 3, the signaling cable H, which is brought up from the bottom of the

sea, is secured by means of a junction sleeve M to the supporting body K. Two steel hawsers T₁ and T₂ which are brought out at right angles to the cable loop anchor the supporting body to the bottom of the sea. The cable is connected to the amplifier in the junction sleeve M by means of the leading-in cables E and A which hang down freely in long loops about 150 metres long and which are led in the holes F formed in the supporting body. They are secured to the casing of the amplifier in an articulated manner. In order to prevent sharp bending or twisting of the cable, rollers R are placed in the loops, which rollers are held at a fixed distance from one another and are weighted by means of a weight Q. The size of the supporting body K is determined by the required buoyancy. The supporting body has to carry the sea cable in so far as it is taken up from the bottom of the sea, the anchoring hawsers, the connecting cable and the amplifier.

Let us assume that in the case of a water depth of 5,000 metres the water weight of the cable is 30 tons, the water weight of two anchoring hawsers 12 tons, the water weight of the connecting cable 3 tons, the water weight of the amplifier 4 tons and the water weight of the casing and stays of the supporting body 3 tons. Let us also assume that there is an excess of buoyancy of the supporting body of 2 tons. The useful buoyancy of the floating body must therefore be 54 tons. As the specific gravity of cork is 0.2, the floating body must have a capacity of about 67.5 cu. m. A supporting body of the said shape has this capacity when the dimensions are as follows:—

40	Upper diameter	6 metres
	Lower diameter	3 metres
	Height	6 metres
	Depth	3 metres

45 The mounting of the amplifier station when the cable is laid does not encounter any fundamental difficulties. After the mounting of the cable and of the connecting cable to the supporting body on board the cable steamer, the supporting body is let down into the water. The steamer lays the cable whilst the other work is done from an auxiliary ship. First of all the supporting body floats on the surface of the sea. By paying 50 out the anchoring hawsers on both sides and by sufficiently loading the supporting body by additional weights which are lowered on ropes from the ship and held in position therefrom, the supporting body is pressed 55 down to a water depth of over 100 metres and is anchored. The additional weight is then removed and the amplifier is let down, which 60 amplifier is inserted exactly into the conical depression of the supporting body by the 65 guiding of the leading-in cables.

The indication of the locality of the amplifier station at the surface of the sea by means of buoys which are secured to the station is unsuitable, as in this way impart forces, which are produced by the wave movement of the sea surface, are transmitted to the station. For this reason a plurality of separately anchored buoys are laid out in the neighborhood of the station. They serve not only as an indication of the locality of the station but also as an auxiliary means to keep the ship exactly in position when operations have to be effected at the station.

70 The finding of the loop S of the amplifier can then be effected by means of a searching anchor or by means of a mine searching device quickly and reliably in a known manner. However, also in the case when the buoys are made loose and driven away by great storms, the station can easily be found 75 by means of searching loops hanging down far below which are dragged along by two ships at right angles to the direction of the cable. In this case the locality may be known 80 only within one or more square sea miles. Use may also be made of echo soundings.

85 The station having been found, the ship keeps in position above it approximately vertically. The rope loop S is gripped by means of a gripping anchor and the amplifier is 90 pulled up.

95 The construction of amplifier station of deep-sea signaling cable hereinbefore described is determined in the first instance 100 by the electrical conditions of operation of the amplifier. Accumulators or dry cells are used as sources of current. There are dry elements which, with an intermittent supply of current of not more than $\frac{1}{10}$ ampères, give an output of 100 ampère-hours. For the 105 heating of the thermionic tubes so many cells are connected in parallel with one another that the supply of current for the heating of the amplifying tubes per cell can be kept within the order of 2 millamps, whereby the 110 life of the cells in view of their capacity can be maintained for about 5,000 hours of operation. In practice, however, such a long life is not attained. For this reason a plurality 115 of groups of spare cells are provided, which are switched on one after the other as required by means of a minimum relay. In this case use is preferably made of cells in which the electrolyte is automatically filled by means of a minimum relay. Similar arrangements are provided for the anode batteries and for the insertion of substitute thermionic tubes. In this way it is possible to 120 operate the amplifier station for several years without attention, assuming that the operation lasts 4-6 hours per day and that the switching on and switching off of the amplifiers is effected by means of the signaling current. But also in the case when continuous 125 operation of the amplifiers is necessary,

it is possible to maintain a minimum period of operation of at least one year without attention, since sufficient space and buoyancy are available for the spare batteries. The 6 exchanging of the cells and tubes may be effected from on board any large freight steamer in a short time and without interrupting operations.

What I claim is:—

10 1. An amplifier station for deep-sea signaling cables comprising in combination with the signaling cable, an unsinkable supporting body, to which the said cable is led from the deep sea, means for anchoring the said body at a floating water depth where there are no wave movements or only weak wave movements, an amplifier, a water-tight and pressure-resistant casing freely mounted on the said supporting body and containing the said amplifier and means electrically connecting the signaling cable with the amplifier, the said means being such as to allow the casing containing the amplifier to be lifted off the supporting body and be brought 20 to the surface of the sea, without the electrical connection between the signaling cable and the amplifier being interrupted.

25 2. An amplifier station for deep-sea signaling cables as claimed in claim 1, in which the upper surface of the supporting body is a hollowed-out cone and the lower part of the amplifier casing is conical and fits in the said hollowed-out cone in the supporting body.

35 3. An amplifier station for deep-sea signaling cables as claimed in claim 1, having a junction sleeve on the supporting body to which the deep-sea signaling cable is secured, in combination with two flexible cables in the 40 form of tensioned loops hanging down into the water, one end of each of them being connected to the said junction sleeve and the other end to the amplifier.

45 4. An amplifier station for deep-sea signaling cables as claimed in claim 1, having a junction sleeve on the supporting body to which the deep-sea signaling cable is secured, in combination with two flexible cables in the 50 form of tensioned loops hanging down into the water, one end of each of them being connected to the said junction sleeve and the other end to the amplifier, and in further combination with rollers placed in the loops 55 at a fixed distance from one another and with weights for weighting the rollers.

55 5. An amplifier station for deep-sea signaling cables as claimed in claim 1, having a junction sleeve on the supporting body to which the deep-sea signaling cable is secured, in combination with two flexible cables in the 60 form of tensioned loops hanging down into the water, one end of each of them being connected to the said junction sleeve and the other end to the amplifier, and means in the

supporting body for guiding the connections of the loops to the amplifier.

6. An amplifier station for deep-sea signaling cables as claimed in claim 1, having a junction sleeve on the supporting body to 70 which the deep-sea signaling cable is secured, in combination with two flexible cables in the form of tensioned loops hanging down into the water, one end of each of them being connected to the said junction sleeve and the 75 other end to the amplifier, and in further combination with rollers placed in the loops at a fixed distance from one another and with weights for weighting the rollers, and means in the supporting body for guiding the connections of the loops to the amplifier. 80

7. An amplifier station for deep-sea signaling cables as claimed in claim 1, in combination with a wire rope for supporting the amplifier, the said wire rope forming a loop, 85 in combination with a floating body for maintaining the said loop and amplifier in a vertical position.

8. An amplifier station for deep-sea signaling cables as claimed in claim 1, in combination with a supporting frame to which the casing of the amplifier is secured and in further combination with a wire rope secured to the said supporting frame and forming a 90 loop and with a floating body for maintaining the said loop in a vertical position. 95

9. An amplifier station for deep-sea signaling cables as claimed in claim 1, in which the supporting body consists of a reinforced hollow body made of sea-water resisting material, the said hollow body containing a 100 light material such as cork.

In testimony whereof I have signed my name to this specification.

HERMANN HUNKEL.
